VALVE MECHANISM FOR ROCK DRILLS

Albert R. Mack, Phillipsburg, N. J., assignor to
Ingersoll-Rand Company, Jersey City, N. J., a
corporation of New Jersey

Application April 26, 1937, Serial No. 138,967

4 Claims. (Cl. 121—25)

This invention relates to rock drills, and more particularly to a valve mechanism for distributing the pressure fluid to the percussive element of the rock drill.

5 The objects of the invention are to obtain a heavy blow of the percussive element against the working implement, to minimize the power cost of operating the tool, and to effect a rapid distribution of pressure fluid and a consequent 10 rapid action of the percussive element.

10 Other objects will be in part obvious and in part pointed out hereinafter.

In the drawing accompanying this specification and in which similar reference numerals refer to similar parts,

Figures 1 and 2 are longitudinal views, in section, showing the valves in the different limiting positions which they will occupy in operation.

Referring more particularly to the drawing, 20 20 designates a cylinder of a rock drill having a piston chamber 21 to accommodate a reciprocating hammer piston 22 which controls a free exhaust port 23 for the piston chamber 21.

25 A closure is provided for the front end of the piston chamber in the form of a front cylinder washer 24 and a back cylinder washer 25 performs a like function for the rear end of the piston chamber 21. The back cylinder washer 25 is arranged within an enlarged bore 26 in the rear 30 end of the cylinder 20 and serves as a seat for valve mechanism comprising, among other elements, a valve chest 27 which may be clamped in position by a back head 28 and the usual side bolts (not shown).

35 In the form of the invention illustrated, a pair of plates 29 and 30 are interposed between the back head 28 and the valve chest 27 and bored to receive an end of a bushing 31 of which the opposite end extends into the back cylinder 40 washer 25. The internal surface of the bushing 31 serves as a bearing for a rifle bar 32, where- 40 with the piston 22 is slidably interlocked, and the rifle bar 32 may be provided with the usual pawl and ratchet devices for effecting step-by-step

45 rotary movement of the piston 22 and thus, through suitable mechanism (not shown), of a working implement which the piston is intended to actuate.

50 The valve chest 27 comprises an intermediate plate 33 and end plates 34 and 35 seating against the plate 30 and the back cylinder washer 25, respectively. The plates 33, 34 and 35 are suitably bored to form a valve chamber 36 for which the periphery of the bushing 31 serves as an inner bounding surface. Intermediate the ends

of the valve chamber 36, and located in the plate 33, is an annular groove 37 into which pressure fluid is introduced from a source of supply by a passage 38 extending through the plates 29, 30, 34 and 33.

5 In the portions of the valve chamber lying forwardly and rearwardly of the groove 37 are valves 39 and 40, respectively, for controlling the admission of pressure fluid to the ends of the piston chamber 21. The valves are of substantially the same conformation, each being of the sleeve type encircling the bushing 31 and having a peripheral flange 41 intermediate its ends. There are, however, essential differences in the manner of application of the forces controlling the action of 15 the valves. Each valve is provided with a series of longitudinal passages 42 which extend entirely through the wall of the valve and are in constant communication with the annular groove 37.

The pressure fluid passing through the passages 20 42 of the valve 40 passes, in the open position of said valve, through a channel 43 defined by the plates 29 and 30, thence through an inlet passage 44 to the front end of the piston chamber 21, and the pressure fluid flowing through the 25 passages 42 of the valve 39 flows through the front end of the valve chamber 36, an annular groove 45 in the plate 35 and through an inlet port or ports 46, in the back cylinder washer 25, into the rear end of the piston chamber 21. The 30 passages 42 are off-set with respect to the ports 46 and, in the closed position of the valve 39, are sealed by the back cylinder washer 25.

The inlet opening 47 of the channel 43 is, likewise, off-set with respect to the ports 42 in the 35 valve 40 and thus, in the closed position of said valve, the plate 30 will serve to seal the rear ends of the adjacent passages 42.

Preferably, a small leak port 48 is formed in the back cylinder washer 25 to assure a constant 40 slight admission of pressure fluid into the rear end of the piston chamber to facilitate and assure starting of the hammer piston 22 at the beginning of each period of operation.

The opposing surfaces of the flange 41 of the 45 valve 39 constitute front and rear actuating surfaces 49 and 50 which are intermittently subjected to pressure fluid valved thereto by the piston 22. Pressure fluid is conveyed to the 50 actuating surface 49 by a kicker passage 51 leading from the piston chamber 21 at a point forwardly of the exhaust port 23 to the groove 52 containing the flange 41. A second kicker passage 53 leads from a point in the piston chamber 55

rearwardly of the exhaust port 23 to the rearward end of the groove 52.

The portion of the valve 39 lying forwardly of the flange 41 is of larger diameter than the rearward portion and the front or end surface of the valve constitutes a holding surface 54 which is exposed to pressure fluid flowing thereover to the inlet passage 46 for holding the valve 39 in its rearmost limiting position. Similarly, the surface of the valve confronting the groove 37 serves as a holding surface 55 against which pressure fluid constantly acts. Such pressure fluid assists in shifting the valve 39 forwardly and is the force that holds the valve in its foremost limiting position.

The opposing end surfaces of the valve 40 also constitute holding surfaces 56 and 57. That designated 56 is the surface of larger area and is constantly exposed to pressure fluid in the groove 37. The surface 56, moreover, serves as an actuating surface against which the pressure acts for shifting the valve rearwardly to close communication between supply and the front inlet passage 44.

25 An opposing actuating surface 58 is located on the rear end of the flange 41 of the valve 40, and a passage 59 leads from the rear end of the groove 60 containing the flange 41 to a point near the forward end of the piston chamber 21. More 30 specifically, the passage 59 is a tripper passage and pressure fluid is constantly introduced thereto by a leak port 61 leading from the groove 37.

The front end of the groove 60 is vented to the atmosphere through a passage 62 extending 35 through the valve chest and the cylinder 20.

The operation of the device is as follows: With the valves and the piston in the rearmost limiting positions, as illustrated in Figure 1, the passages 42 of the valve 40 are sealed by the plate 30 and the valve 40 is held immovable by the pressure fluid acting against the surface 56. Pressure fluid then flows through the passages 42 of the valve 39 into the front end of the valve chamber 36, thence through the groove 45 and the inlet passages 46 into the rear end of the piston chamber 21 and drives the piston 22 forwardly on its working stroke. The valve 39 is held in the open position described by the pressure fluid acting against the holding surface 54.

50 During its forward movement the piston uncovers the kicker passage 53. Pressure fluid then flows into the groove 52 and, acting against the actuating surface 50, throws the valve 39 forwardly to cut off the flow of pressure fluid into 55 the rear end of the piston chamber. This force is augmented by the pressure fluid acting constantly against the surface 55 and which serves, after the valve has been shifted, to hold the valve seated against the back cylinder washer 25.

60 Immediately after uncovering the kicker passage 53 the piston uncovers the free exhaust port 23 to communicate the rear ends of the piston chamber and the groove 52 to the atmosphere. Simultaneously with the uncovering of the exhaust port 23, or immediately thereafter, the piston covers the tripper passage 59. The pressure fluid flowing into the tripper passage 59 will then be entrapped therein and act against the actuating surface 58 and move the valve 40 forwardly.

In the new position of the valve 40 pressure fluid flows from the groove 37 through the passages 42 of the unseated valve, thence through the channel 43 and the inlet passage 44 into the 75 front end of the piston chamber 21 to return the

piston 22 to its initial position. During the charging of the front end of the piston chamber the valve 40 is held immovable by the pressure fluid flowing over the holding surface 57 and that acting against the actuating surface 58.

The valve 40 remains in the open position until the front end of the piston 22 again uncovers the exhaust port 23, whereupon the pressure fluid employed for actuating the piston and that acting against the actuating surface 58 is exhausted to the atmosphere. The pressure fluid acting against the surface 56 will then immediately shift the valve 40 against the plate 30 and cut off communication between the inlet passage 44 and the groove 37. However, immediately before the piston uncovers the exhaust port 23, during the rearward stroke of the piston, it will uncover the kicker passage 51 and pressure fluid then flows into the front end of the groove against the actuating surface 49 and lift the valve to again establish communication between the source of supply and the rear end of the piston chamber.

I claim:

1. In a fluid actuated rock drill, the combination of a casing having a piston chamber and a piston therein, an exhaust port for the piston chamber, a valve chest having a valve chamber, inlet passages leading from the valve chamber to the piston chamber, valves in the valve chamber for controlling the inlet passages, opposed actuating surfaces on one valve of which one actuating surface is constantly exposed and another actuating surface intermittently exposed to pressure fluid for throwing the valve, and opposed actuating surfaces on the other valve intermittently exposed to pressure fluid for throwing the said other valve.

2. In a fluid actuated rock drill, the combination of a casing having a piston chamber and a piston therein, an exhaust port for the piston chamber, a valve chest having a valve chamber, inlet passages leading from the valve chamber to the piston chamber, a valve in the valve chamber to control an inlet passage and having an actuating surface intermittently exposed to pressure fluid for throwing the valve to one limiting position, a holding surface on the valve intermittently exposed to pressure fluid for holding the valve in such position, an opposed actuating surface on the valve constantly exposed to pressure fluid for throwing the valve to another limiting position and for holding the valve, a second valve in the valve chamber for controlling another inlet passage and having opposed actuating surfaces intermittently exposed to pressure fluid for throwing said second valve, and opposed holding surfaces on said second valve exposed to pressure fluid for holding said second valve.

3. In a fluid actuated rock drill, the combination of a casing having a piston chamber and a piston therein, an exhaust port for the piston chamber, a valve chest having a valve chamber, inlet passages leading from the valve chamber to the piston chamber, a valve in the valve chamber to control an inlet passage, an actuating surface on the valve intermittently exposed to pressure fluid for throwing the valve to one limiting position, a holding surface on the valve intermittently exposed to pressure fluid for holding the valve in such position, an opposed actuating surface on the valve of greater area than the holding surface and being constantly exposed to pressure fluid for throwing the valve to another limiting position and for holding the

valve, a second valve in the valve chamber for controlling another inlet passage and having opposed actuating surfaces intermittently exposed to pressure fluid for throwing said second valve, a pressure surface on the said second valve constantly exposed to pressure fluid for throwing and holding said second valve, and a holding surface on said second valve of greater area than the pressure surface and being intermittently exposed to pressure fluid for holding the said second valve.

4. In a fluid actuated rock drill, the combination of a casing having a piston chamber and a piston therein, an exhaust port for the piston chamber, a valve chest having a valve chamber, inlet passages leading from the valve chamber to the piston chamber, a valve in the valve chamber to control an inlet passage, an actuating surface on the valve intermittently exposed to pressure fluid for throwing the valve to admit pressure fluid to one inlet passage, a holding

surface exposed to pressure fluid flowing to the inlet passage for holding the valve, an opposed actuating surface on the valve exposed constantly to pressure fluid for returning and holding the valve and being of greater area than the holding surface, a second valve in the valve chamber to control another inlet passage and having opposed actuating surfaces intermittently exposed to pressure fluid for throwing said second valve, a holding surface on said second valve exposed intermittently to pressure fluid for holding said second valve in position to admit pressure fluid to the associated inlet passage, and an opposed holding surface on said second valve of smaller area than the last mentioned holding surface constantly exposed to pressure fluid to assist in throwing the valve for cutting off the flow of pressure fluid to the associated inlet passage and for holding the valve.
